DESIGN FOR A TABLE COVER.

Application filed November 21, 1923. Serial No. 7,841. Term of patent 3½ years.

To all whom it may concern:

Be it known that I, CARRODUS BASTOW, a citizen of the United States, and a resident of Allwood, State of New Jersey, have invented a new, original, and ornamental Design for a Table Cover, of which the following is a specification, reference being had to the accompanying drawing, forming a part thereof, wherein the essential elements of the design comprise a panoramic Dutch landscape within a circularly arranged border, the essential feature of which comprises a windmill theme. The design

is further ornamented by the addition of corner medallions representing waterscapes, accentuated respectively by the figures of a boy and a girl, a windmill, and by cows and vessels.

The figure represents a plan view of my design as particularly adapted to a table cover.

I claim:

The ornamental design for a table cover, substantially as shown and described.

CARRODUS BASTOW.
